(57) **CLAIM**

The ornamental design for a drain strainer, as shown and described.

DESCRIPTION

FIG. 1 is an exploded top-front-left perspective view of a drain strainer showing my new design;

FIG. 2 is an exploded bottom-rear-right perspective view thereof;

FIG. 3 is an exploded front elevational view thereof;

FIG. 4 is an exploded rear elevational view thereof;

FIG. 5 is an exploded top plan view thereof;

FIG. 6 is an exploded bottom plan view thereof;

FIG. 7 is an exploded right elevational view thereof;

FIG. 8 is an exploded left elevational view thereof;

FIG. 9 is an enlarged top perspective view thereof in an assembled configuration; and,

FIG. 10 is an enlarged bottom perspective view thereof in the assembled configuration.
